UNITED STATES PATENT OFFICE.

BELLA WELLHAUSEN, OF AMITE, LOUISIANA.

TATTING-SHUTTLE WINDER.

1,250,399.

Specification of Letters Patent. Patented Dec. 18, 1917.

Application filed March 22, 1917. Serial No. 156,675.

To all whom it may concern:

Be it known that I, BELLA WELLHAUSEN, a citizen of the United States, residing at Amite, in the parish of Tanipahoa and 5 State of Louisiana, have invented certain new and useful Improvements in Tatting-Shuttle Winders, of which the following is a specification.

The present invention relates broadly to 10 a tatting shuttle holder, and more specifically to a supporting device engageable with a shuttle, by means of which the sides of the latter may be separated to facilitate the placing of the thread therebetween.

15 Tatting shuttles as at present manufactured comprises a thread receiving post, to the opposite end of which the sides or flanges of the shuttle are connected. The sides or flanges are curved toward each 20 other so that the points of one side are spaced from the points of the other side a distance barely sufficient to permit the passage of the thread therebetween. Therefore it will be seen that to take the shuttle 25 in one hand and attempt to wind the thread between the sides of the same with the other hand is, owing to the close proximity of said sides, a task both slow and tedious, and one that can be quickly and efficiently performed only by those skilled from practice.

30 With the foregoing in mind, an object of the present invention is to provide means engageable with a shuttle for separating the sides of the same, to permit the thread 35 to be readily placed therebetween.

Another object of this invention is to provide a supporting device of simple construction, which may be held in one hand and when engaged with a shuttle greatly 40 facilitates the filling operation of the same.

A further object is to provide a device of the character described, which being formed of a single piece of material, bent to the shape necessary to its operation, constitutes 45 an article of manufacture, which may be placed on the market at a minimum amount of cost.

The above and other objects and advantages of the invention will be in part described, and in part understood from the 50 following description of the present preferred embodiment the same being illustrated in the accompanying drawings, in

which, Figure 1 is a side elevational view of my device in a detached position. 55

Fig. 2 is a view similar to Fig. 1 showing the device applied to a tatting shuttle.

Fig. 3 is a top plan view.

Fig. 4 is a cross sectional view taken on line 4—4 of Fig. 3 and, 60

Fig. 5 is a longitudinal sectional view taken on line 5—5 of Fig. 4.

The usual procedure in winding thread upon a tatting shuttle is to take the shuttle in one hand, and wind the thread thereon 65 with the other hand, which, owing to the construction of the shuttle, as previously set forth, is both awkward and difficult, and therefore the present invention has been designed to render the operation referred to, 70 less irksome, and more easy of accomplishment, and to this end consists briefly, of a single strip of metal bent intermediate its ends to form a prolonged loop serving as a handle portion, the free ends of the loop 75 being reversely bent to extend at right angles to said loop portion. The free ends of the loops in their bent position form a support for a shuttle, and have the marginal edges thereof folded inwardly to embrace 80 the marginal edges of the shuttle.

For a more detailed description reference is had to the drawing in which the numeral 1 indicates the device which is formed from a single strip of resilient metal, bent intermediate its ends as indicated at 2 to form a pair of spaced spring arms 3 and 4. The free ends of said arms 3 and 4 are enlarged, as indicated at 7 and shown to advantage, in Figs. 3 and 5, and are bent in reverse 85 direction as at 8 to extend outwardly at substantially right angles to the arms 3 and 4. The said free ends 5 and 6 of the arms are preferably slightly inclined toward the junction of the arms 3 for a purpose hereinafter set forth, and have the marginal edges thereof folded inwardly to engage over the marginal edges of a tatting shuttle as indicated at 9 and advantageously shown in Fig. 2. 100

As is known to those familiar with the art the sides of the tatting shuttles in general use, have the marginal edges thereof so curved, as to present a flat elliptical configuration, and with this in view the enlarged ends of applicant's device, which sup-

port the shuttle flange, are formed in such a manner, that the marginal edges thereof when folded inwardly, follow a curve corresponding to the curvature of the shuttle 5 sides and are adapted to snugly embrace the marginal edges of the same, this being clearly shown in Fig. 3.

To use my device one end of the shuttle is engaged beneath the inturned marginal 10 edges 9 of the arm 3, and upon pressing the arms together the other end of the shuttle is subsequently engaged by the marginal edges 9 of the arms 4. The sides of a shuttle are usually bow shape, and therefore it 15 will be seen that, as the supporting ends 5 and 6 are inclined as has been previously described, the side of the shuttle engaged by the marginal edges of the same will be so distorted from its normal position, as 20 to increase the space between the points of the shuttle.

Having thus fully described my inven-

tion, what I claim and desire to secure by Letters Patent is:

1. A shuttle holder, consisting of a single 25 piece of metal bent intermediate its ends to provide a handle portion, the free ends of said handle being bent to form a shuttle support and having the lateral edges thereof folded inwardly as and for the purpose 30 specified.

2. A device of the character described, including a handle comprising spaced arms having the free ends thereof turned outwardly to provide shuttle supports, said 35 outturned ends having their lateral margins folded inwardly and longitudinally curved to provide shuttle retaining members.

In testimony whereof I affix my signature in presence of two witnesses:

MRS. BELLA WELLHAUSEN.

Witnesses:

JEANNETTE DEUSON,
ELOISE WELLHAUSEN.
